ATTORNEY

UNITED STATES PATENT OFFICE.

FRANCESCO GASCO, OF NEW YORK, N. Y.

RAZOR-BLADE SHARPENER.

Application filed November 3, 1922. Serial No. 598,703.

To all whom it may concern:

Be it known that I, FRANCESCO GASCO, a citizen of Italy, and a resident of New York city, in the county and State of New York, have invented certain new and useful Improvements in a Razor-Blade Sharpener, of which the following is a specification.

Among the principal objects which the present invention has in view are: To provide means for holding thin razor blades at the proper angle while stropping the same; to provide means for quickly adjusting the blade being sharpened in sharpening position; to furnish a holder for the blade which may be easily cleansed and rendered sanitary.

Drawings.

Figure 1 is a top plan view of a sharpener constructed and arranged in accordance with the present invention showing in conjunction therewith a thin razor blade disposed as in service.

Figure 2 is a side edge view of the same. Figure 3 is a similar view showing the plate screwing portion of the sharpener detached from the handle and in open position for the removal or insertion of the blade.

Figure 4 is a bottom view of the same.

Figure 5 is a cross section taken as on the line 5—5 in Fig. 2.

Figure 6 is a cross section taken as on the line 6—6 in Fig. 2.

Figure 7 is a similar view showing the working position of the sharpener inverted from that shown in a former figure.

Description.

As seen in the drawings, the holder 12 for the blade 13 has a flat upper surface from which protrudes pins 14 so disposed as to extend through the perforations with which the blades 13 are usually provided. The under or reverse side of the holder 12 is thickened at the center to a height equal to the projection of the pins 14 above the blade 13 when in service. The thickness referred to is herein designated as the ridge 15 and can be best seen in Figures 4, 6 and 7. The ridge 15 provides a rocking surface for the sharpener when resting on a

strop 16. The same function is performed by the pins 14 when desired, as shown in Figures 6 and 7 of the drawings.

To hold the blade 13 in service position the spring detent tongue 17 is rigidly secured on the holder 12 by means of the rivets 18. As seen in Figures 1 and 2, the rivet 19 is at the narrowed end of the wedge 20 with which the holder is provided and which facilitates it being driven into the wooden handle 21 with which the sharpener is preferably provided.

Beneath the tongue 17, the holder has a recess 22 into which the inclined underside of the detent 17 leads.

At the end of the holder opposite that having the detent 17 is secured a resilient finger 23. The finger 23 extends from a clamp 24 through the elongated slot 25 of which extends a stud screw 26. The rear end of the clamp 24 has a small handle 28 by which the clamp 24 is moved forward or retracted as it is desired to adjust the finger 23 on the blade 13. For applying pressure to the blade 13 a nut 27 is furnished, the threads of which engage the threads of the screw 26. When the nut 27 is set up on the screw 26, the clamp 24 is forced down on the holder 12 with the result that the finger 23 presses on the end of the blade 13 which has been exposed on the holder with the full strength of the resilient metal of which the said finger is composed. When the nut is retracted as seen in Figure 3 of the drawings, the blade 13 may be readily and quickly lifted from the holder 12 and from engagement with the pins 14.

When it is desired to clean the holder, the nut 27 is removed and the clamp 24 is lifted from the holder 12 so that the meeting surfaces of the said clamp and the holder may be thoroughly cleaned.

When employing a holder constructed and arranged in accordance with the present invention, the operation of inserting the blade is as follows:

The nut 27 is retracted to permit the clamp 24 to be rocked to the position shown in Figure 3 of the drawings. The blade 13 is then installed. This is accomplished by, first placing one end of the blade under the inclined surface of the tongue 17 sufficiently to align the perforations with which the

- blade 13 is provided, with the pins 14. The blade is then depressed to rest upon the holder 12, the pins 14 protruding through the perforations mentioned. The nut 27 is 5 then set up forcing down the clamp 24 and flexing the finger 23 in the position shown in Fig. 2 of the drawings. The finger 23 and the tongue 17 now prevent the blade 13 from being lifted from the holder 12.
- 10 Usually the blade is sharpened by resting the holder on the strop 16, the ridge 15 being presented to the said strop to form a rock- 15 ing surface thereunder. When thus placed on the strop, the holder is carried to the one end of the strop dragging the rear edge of the blade on the stropping surface. When the blade has been carried to the far end of 20 the strop, the holder is rocked on the ridge 16 preparatory to returning the blade to the initial position and dragging the opposite 25 edge of the blade. This is continued as long as the operator desires, when by releasing the nut 27, the blade 13 is lifted from engagement with the tongue 17 and finger 23 and is inverted or turned over on the holder 12. When the clamp 24 is again forced down, the tongue 17 and finger 23 hold the blade so that the opposite sides of the edges 30 of the blade is in position to be stropped.
- 35 As shown in Figure 7 of the drawings, if the operator desires to spare himself the trouble of re-adjusting the blade, he may do

so using then the pins 14 for rocking the holder and the blade carried thereby.

Claims.

1. A razor blade sharpener comprising a holder having a flat supporting surface and projections therefrom for registering with razor blades; means for retaining blades in service position on said holder; and means for releasing said blade from said retaining means, said means embodying a screw-threaded member adapted for impingement upon and retraction from said holder, and means associated therewith for engaging said blade when on said holder, said means consisting in a resilient finger extensible over said blade. 40
2. A razor blade sharpener comprising a holder having a flat supporting surface and projections therefrom for registering with razor blades; means for retaining blades in service position on said holder; and means for releasing said blade from said retaining means, said means embodying a screw-threaded member adapted for impingement upon and retraction from said holder, and means associated therewith for engaging said blade when on said holder, said means 45 consisting in a resilient finger extensible over said blade, said finger having a sliding engagement with said nut. 50
